US00D973734S

(12) **United States Design Patent** (10) **Patent No.:** **US D973,734 S**
(45) **Date of Patent:** **** Dec. 27, 2022**

(54) **BLIND SHEAR**

(71) Applicant: **NEXUS ENERGY TECHNOLOGIES INC.**, Red Deer County (CA)

(72) Inventor: **Ryan Smith**, Red Deer (CA)

(73) Assignee: **NXL TECHNOLOGIES INC.**, Edmonton (CA)

(**) Term: **15 Years**

(21) Appl. No.: **29/700,833**

(22) Filed: **Aug. 6, 2019**

(51) LOC (13) Cl. **15-09**

(52) U.S. Cl.

USPC **D15/139**

(58) **Field of Classification Search**

(57) **CLAIM**

The ornamental design for a blind shear, as shown and described.

DESCRIPTION

FIG. 1 is a top perspective view of the blind shear in an open configuration;

FIG. 2 is a bottom perspective view thereof in the open configuration;

FIG. 3 is an exploded top perspective view thereof;

FIG. 4 is an exploded bottom perspective view thereof;

FIG. 5 is a second exploded bottom perspective view thereof;

FIG. 6 is a second exploded top perspective view thereof;

FIG. 7 is an enlarged front view thereof in the open configuration;

FIG. 8 is an enlarged rear view thereof in the open configuration;

FIG. 9 is a right view thereof in the open configuration;

FIG. 10 is a left view thereof in the open configuration;

FIG. 11 is a top view thereof in the open configuration;

FIG. 12 is a bottom view thereof in the open configuration;

FIG. 13 is an enlarged top perspective view thereof in a closed configuration; and,

FIG. 14 is an enlarged bottom perspective view thereof in the closed configuration.

1 Claim, 7 Drawing Sheets
